A. EMSLEY

COMBINATION DRAWERS AND ABDOMINAL SUPPORT FOR MEN

Filed July 14, 1923

Inventor
Annie Emsley

By Thomas A. Jenkins Jr.

Attorney

UNITED STATES PATENT OFFICE.

ANNIE EMSLEY, OF PROVIDENCE, RHODE ISLAND.

COMBINATION DRAWERS AND ABDOMINAL SUPPORT FOR MEN.

Application filed July 14, 1923. Serial No. 651,578.

To all whom it may concern:

Be it known that I, ANNIE EMSLEY, a citizen in the United States, residing at Providence, in the county of Providence and State of Rhode Island, have invented 5 certain new and useful Improvements in Combination Drawers and Abdominal Support for Men, of which the following is a specification.

10 My invention relates to improvements in combination drawers and abdominal supports for men.

The advantages of a one-piece undergarment consisting of a pair of drawers with a 15 re-enforced abdominal supporting portion are obvious. The discomfort of a separate truss or bandage underneath the drawers which are made to fit the wearer without the bandage, is obviated, and the support is at 20 all times conveniently accessible with the drawers. I am aware that broadly speaking combined drawers and loose fitting unfashioned abdominal supports are old, but I believe that I for the first time incorporate 25 adjustable truss features into this type of undergarment. A plurality of belts or loose fitting bandages have been used, but I furnish more support than these by incorporating flexible pieces of stiff boning, whether 30 metallic or otherwise, in the abdominal supporting portion itself. It is obvious that the exact position of these re-enforcing strips may be varied so as to concentrate the desired extra pressure on any spot on the 35 waist or abdomen, and thus provide truss re-enforcement therefor. In addition, I construct my supporting portion of suitable width, larger in front than in the rear, in order to lift up the stomach in the front, 40 and to protect the kidneys in the rear, and fashion it so as to suitably conform to and support the entire waist. The vent and lacing in the rear renders it readily adjustable to furnish any desired amount of pressure, 45 and the front is similar to that of an ordinary pair of drawers.

One object of my invention is to provide a combination drawers and abdominal support into which truss features are incorporated to furnish the desired amount of medicinal support to the wearer.

A further object of my invention is to provide an adjustable combination drawers and abdominal support which is in reality 55 drawers, and may be put on and taken off with the same facility as ordinary drawers,

but which has abdominal supporting means incorporated therein.

A further object of my invention is to provide a novel undergarment for men 60 fashionably inclined.

A further object of my invention is to provide an obesity reducing undergarment, the stomach not only being supported, but the stouter upper portion thereof also tending 65 to produce a sweat, which tends to reduce the wearer's waist.

A further object of my invention is to provide a more sanitary belt than hitherto 70 which being attached to the drawers, is automatically washed each week with them.

These and such other objects of my invention as may hereinafter appear will be understood from a description of one embodiment thereof, such as is illustrated in 75 the accompanying drawings.

In the drawings, Fig. 1 is a front elevation of my improved combination drawers and abdominal support.

Fig. 2 is a rear elevation of my improved 80 combination drawers and abdominal support. Fig. 3 is a front view of one of the halves of the abdominal supporting portion, part 85 of the layer of fabric being broken away to show the position of the additional supporting elements.

In the drawings, wherein like characters of reference indicate like parts throughout, 90 generally indicates the abdominal supporting or waist portion of my invention. This is preferably constructed out of a closely woven comparatively stout material such as canvas or corset cloth. The outer layer 11 is suitably sewed to the inner layer 95 12 thereof as is shown in Fig. 3. 13 indicates the drawers portion which is suitably sewed or otherwise secured to the lower edge of the waist portion 10. This is preferably constructed of a knitted woolen fabric, 100 though it is obvious that any type of drawers may be employed.

As stated, the waist portion 10 is of a suitable width and is suitably fashioned to conform to the curvature of the body, and 105 is preferably wider at the front, as at 15, to conveniently encompass, raise up and support the stomach and abdomen and preferably narrow in the rear as at 16, to conveniently cover and protect the kidneys. 110 An inspection of the front and rear elevations shown in Figs. 1 and 2, shows how

the drawers portion 13 is more cut away at the front than in the back for this purpose. The waist portion is preferably constructed out of the two half portions 17 and 18, each 5 portion except for the buttons being reversely similarly constructed. To compactly fit the body each half 17 and 18 is preferably cut into three inclined portions 7, 8 and 9 respectively, suitably sewed together as is indicated by the seams 19. The half 17 is provided with the button holes 20 in its front end and the half 18 is provided with the buttons 21 in its front end. It is obvious, therefore, that my invention is 10 constructed so that it may be conveniently put on and taken off like a pair of ordinary drawers. The rear end of each half 17 and 18 is provided with the lacing holes 23. When assembled, the cloth flap 24 loosely 15 binds the halves 17 and 18 together, and protects the wearer from the lacing 25 which adjustably secures the halves 17 and 18 together. Where additional support is 20 needed, horizontally disposed supporting straps 26 may be conveniently inserted between the layers 11 and 12 of the waist portion 10. It is obvious that I have provided a compact combination drawers and 25 abdominal support of improved adjustable 30 fashioned construction.

My invention, however, goes further than this. In addition to providing the novel undergarment heretofore described, I incorporate in garments of this type the truss 35 features now to be described. I insert between the layers 11 and 12 of the stout fabric at intervals throughout the waist belt portion, and secure thereto preferably in a substantially vertical position extra re-enforcing truss elements. These may 40 comprise where some extra support is needed the cords 28 or where greater support is needed the flexible boning strips 29. Whether the boning be whalebone, bone or 45 flexible metal, it furnishes additional support where desired in a manner hitherto unknown in undergarments of this type. As it is possible to vary the position of a truss, so may these additional supporting 50 elements be suitably placed where the greatest amount of support is desired, and the position thereof varied on a physician's prescription. In the embodiment shown which 55 illustrates a garment suitable for an average fat man, not in any particular need of additional support, the boning strips 29 are preferably placed in the front thereof to bring additional pressure to bear against the stomach, and the cords 28 are suitably 60 placed at intervals around the waist. I employ the word "boning" to signify stiff flexible re-enforcing strips whether made out of bone, whalebone, metal or otherwise.

I employ the word "stout," to signify any 65 suitable, strong, durable, flexible material

such as canvas, duck, or any other suitable material.

Though I have shown drawers alone, it is obvious that a union suit conforming to and within the scope of my invention might 70 be made by adding an additional shirt portion above the belt portion of my invention as described.

It is understood that my invention is not limited to the specific embodiment shown, 75 and that various deviations may be made therefrom without departing from the spirit and scope of the appended claims.

What I claim as new and desire to secure as Letters Patent is:

80

1. A one-piece undergarment for men, comprising an abdominal supporting portion constructed out of stout inelastic material fashioned to compactly enclose and support the waist and abdomen, re-enforced by cords and boning strips substantially vertically encased at intervals therein and having additional re-enforcing straps horizontally enclosed therein, and a vented portion in the rear the sides of which may be 85 adjustably laced together, and a drawers portion permanently attached to the lower edge thereof.

85

2. A one-piece undergarment for men, comprising an abdominal supporting portion 90 constructed out of stout inelastic material fashioned to compactly enclose and support the waist and abdomen, re-enforced by cords and boning strips substantially vertically encased at intervals therein and having a vented portion in the rear the 95 sides of which may be adjustably laced together, and a drawers portion permanently attached to the lower edge thereof.

100

3. A one-piece undergarment for men, comprising an abdominal supporting portion 105 constructed out of stout inelastic material fashioned to compactly enclose and support the waist and abdomen, having a vented portion in the rear the sides of which may be 110 adjustably laced together, and a drawers portion permanently attached to the lower edge thereof.

105

4. A one-piece undergarment for men, comprising an abdominal supporting portion 115 constructed out of stout inelastic material fashioned to compactly enclose and support the waist and abdomen, having additional re-enforcing straps horizontally enclosed therein, and a vented portion in the 120 rear the sides of which may be adjustably laced together, and a drawers portion permanently attached to the lower edge thereof.

115

5. As a new article of manufacture, an undergarment for men, comprising the combination of an abdominal supporting belt having re-enforcing strips of boning encased therein, and a drawers portion permanently attached to the lower edge thereof.

125

6. A one-piece undergarment for men,

130

- comprising a boned abdominal supporting belt portion and a drawers portion permanently attached to the lower edge thereof.
7. A one-piece undergarment for men, comprising a boned abdominal supporting belt portion having means for circumferential adjustment and a drawers portion permanently attached to the lower edge thereof.
8. A one piece under-garment for men comprising a boned abdominal supporting belt portion fashioned to compactly enclose and support the waist and abdomen and a drawers portion permanently attached to the lower edge thereof.
9. A one-piece undergarment for men, comprising an abdominal supporting portion constructed out of stout inelastic material wider at the front than at the back and made in two halves, each half being constructed out of three inclined pieces so as to conform to the curvature of the body, and each half having strips of boning and re-enforcing cords substantially vertically encased at intervals therein, the boning being placed where the greatest support is desired and provided with means to adjustably secure the halves together, and a drawers portion secured to the lower edge of said abdominal supporting portion.
10. A one-piece undergarment for men, comprising an abdominal supporting portion constructed out of stout inelastic material wider at the front than at the back and made in two halves, each half being constructed out of three inclined pieces so as to conform to the curvature of the body, and each half having strips of boning and re-enforcing cords substantially vertically encased at intervals therein, the boning being placed where the greatest support is desired and provided with additional re-enforcing straps horizontally encased therein, buttons to join each half together at the front and lacing to adjustably join each half at the rear, and a drawers portion secured to the lower edge of said abdominal supporting portion.
11. A one-piece undergarment for men, comprising an abdominal supporting portion constructed out of stout inelastic material made in two halves, each half being constructed out of three inclined pieces so as to conform to the curvature of the body, and each half having strips of boning and re-enforcing cords substantially vertically encased at intervals therein, the boning being placed where the greatest support is desired, means to adjustably secure the halves together, and a drawers portion secured to the lower edge of said abdominal supporting portion.

In testimony whereof I affix my signature.

ANNIE EMSLEY.
